UNITED STATES PATENT OFFICE.

MICHAEL C. ARMOUR AND FRANK G. BIELEFELD, OF CHICAGO, ILLINOIS,
ASSIGNORS TO THE ADAMS & WESTLAKE MANUFACTURING COMPANY
OF MICHIGAN, OF SAME PLACE.

VAPOR-BURNER.

SPECIFICATION forming part of Letters Patent No. 353,654, dated December 7, 1886.

Application filed May 12, 1885. Serial No. 165,181. (No model.)

To all whom it may concern:

Be it known that we, MICHAEL C. ARMOUR and FRANK G. BIELEFELD, both of Chicago, in the county of Cook and State of Illinois, have invented certain new and useful Improvements in Vapor-Burners for Use in Various Applications, of which the following is a specification, reference being had to the accompanying drawings, and to the letters of reference marked thereon.

The invention is herein described more particularly for application to vapor-stoves.

The object of this invention is, first, to overcome the blowing and puffing of the flame so common to gasoline-burners, and which heretofore has been only partially overcome by packing the burner-pipes with asbestos, gravel, or similar substances, the presence of which is objectionable, from the fact that small particles will work into the aperture of the needle-valve and obstruct the flow of vapor. In order to assist in producing a steady flame, we provide a generating-chamber of much greater capacity than is ordinarily used; and in order to heat said chamber effectively and rapidly we adopt means whereby a more effective flame is produced than has been heretofore provided, so that the vaporization of the gasoline is almost instantaneous.

The object of our invention is, secondly, to provide means for working the needle-valve and cut-off (for regulating the flow of gasoline, and consequently the flame) simultaneously, or by the same act or movement—that is to say, by the simple movement of a lever the cut-off is brought over the needle-point and the flame reduced to a minimum, still remaining lighted, and by another movement of the said lever the cut-off is carried away from the air-tube, allowing the flame to burn at the cap or burner proper.

The third object of our invention is to employ one generator for the vaporization of gasoline for its own burner and other burners, as hereinafter set forth.

In the accompanying drawings, Figure 1 shows a side elevation of our improved generator and burner, applied in a manner here-

inafter specified. Fig. 2 is a vertical section of Fig. 1. Fig. 3 is an elevation of the generator and burner from another point of view. Fig. 4 is a vertical section. Fig. 5 is a sectional plan on the line *x x* of Fig. 3, showing in full lines the cut-off, hereinafter described, open, and the same in dotted lines closed, the full lines showing the lever in the position which it occupies when the needle is at its lowest point, and the dotted showing the position of the lever when the needle is at its highest point and the flame extinguished. Fig. 6 is a vertical section through Fig. 4, the line of section being such that the pipe *e* is cut out, or not seen. Fig. 7 is a top view of the burner-cap, hereinafter described. Fig. 8 is a side view of the same. Fig. 9 is an under side view of the same.

Similar letters of reference indicate similar parts in the respective figures.

Referring more particularly to Fig. 4, the vapor-burner leads by the pipe *a* to the gasoline-tank. (Not shown.) The pipe *a* has communication by means of a threaded thimble, *a'*, with the interior of the cistern *c*, a small jet-opening, *b*, being provided in the thimble, through which the gasoline enters the cistern. The thimble is threaded, so as to be vertically adjustable. A vertical pipe, *e*, reaches from the lower part of the cistern, connecting it with the generator *f*. The lower end of the pipe is sealed by the gasoline, and is threaded, so as to be adjustable.

The generator *f* is constructed with an annular space, *f'*, surrounding the wall *f''*, the space *f'* being in communication with the pipe *e*. The annular space within the generator causes the gasoline to take almost a complete circuit before ignition, whereby the fluid is effectually heated. The lower part of the generator is inclosed for the greater portion of its diameter by the cup *g*, which is secured to the under side of the generator by screws *g'*, and the generator is surmounted by a cap, *g''*. (Shown more particularly in Figs. 7, 8, and 9.)

A vertical needle-valve, *h*, screws into a tube, *h'*, which unites by a branch, *h''*, with a chamber, *i*, which connects by means of the pipe

i' with the inside of the generator *f*, as shown more particularly in Fig. 6. The lower end of the tube *h'*, in which the needle-valve *h* fits, is provided with a drip or igniting cup, *k*.
 5 The needle-valve tube *h'*, which is provided with a minute aperture, *l*, is concentric with an air or induction tube, *m*, which extends through the central aperture of the generator, communicating with the cylindrical or crown portion of the hat-shaped cap *g*'. Around the base of the air-tube *m* turns the collar *n* of the lever *n'*, which lever has an arm, *n''*, connecting with the handle *n'''* and with the lower part of the needle-valve *h*, as shown in Fig. 6.
 10 A tube, *i''*, is connected with the lower part of the chamber *i*, said tube carrying a horizontal needle-valve, *h⁴*, having a handle, *h⁵*. The opposite end of the tube *i''* is provided with a disk, *i'''*, screwed thereon. The horizontal needle-valve *h⁴* is only used, as herein-after described, where one burner is employed to generate vapor for itself and other burners.
 15 The cut-off *o* is pivoted or hung by a support, *o'*, arranged between the tubes *e* *i'*, as shown in Figs. 3, 4, and 5, the operation of which cut-off is as follows: On the lower face of the collar *n* of the lever *n'* is formed a pin or projection, *p*, which enters a slot, *p'*, made in the upper part of the cut-off, so that as the 20 lever is turned movement is imparted to the cut-off, which turns upon its pivot in one direction or the other as the lever is moved.
 25 The following is the operation, it being understood that the burner is only generating vapor for itself, the needle-valve *h⁴* being closed: When the needle-valve *h* is closed by turning lever *n'* into the position indicated in dotted lines in Fig. 5, cut-off *o*, also connected with but moving in a direction opposite to 30 that of lever *n'*, stands with its right extremity over jet-aperture *l*. Supposing the apparatus to be cold, the gasoline on being admitted to the pipe *a* strikes against the top of the cistern *c* and finds its way up the tube *e* to the generator *f*. Lever *n'* being now turned to the 35 left, needle-valve *h* is lowered, aperture *l* partly opened, and the gasoline descends pipe *i'*, Fig. 6, and, passing through the horizontal branch *h''*, reaches the needle-valve aperture *l*, is deflected by the concave bottom of cut-off *o*, which is still suspended in position over aperture *l*, and trickles down the sides of the vertical pipe *h'* to the drip or igniting cup *k*. Thereupon the supply through jet-opening *l* must be 40 shut off entirely. The gasoline in igniting-cup *k* having been ignited, the flame is directed toward the generating-chamber, passing up on each side of cut-off *o*, suspended above the cup, and the heating of the generator begins.
 45 When the gasoline in the igniting-cup has been almost consumed, the cut-off must be moved so as to partly open the needle-valve aperture *l*. The generator having been heated by the burning of the fluid in the igniting-cup *k*, the 50 lever must then be thrown fully over, so as to

entirely open the aperture *l*. This position is that indicated in full lines in Fig. 5, in which cut-off *o* is moved away from over needle-valve aperture *l* and from under air-tube *m*, leaving a free passage for the gasoline up into the air-tube. The ignition at the burner occurs immediately with the opening of the aperture, the gasoline shooting up with atmospheric air through the air-tube *m* into the spaces *q q'* of the cap, and falling thence through the annular space *q''* to the cup *g*, from which a supplemental flame arises, the object of which is to heat the burner. A portion of the mingled atmospheric air and gasoline which is projected into space *q* escapes through radial slots in the cap, forming flat narrow flames. The crown of the hat-shaped cap is provided with a series of perforations, *r*, and the flange or brim with a series of slots, *r'*, the perforations and slots being in line, Figs. 4, 7, and 8, 85 the effect of the union of the two series of jets (viz., those emanating from the perforations and those from the slots) being a greenish flame, which is found to be much more effective than the flame ordinarily produced in gasoline-burners. Now, supposing the flame to be full on and it is desired to stop cooking without extinguishing the flame, the lever *n'* must be moved from the position shown in full lines in Fig. 5 to such position as is indicated, say, 90 by the dotted line *z*, which has the effect of nearly closing the needle-valve aperture *l* and nearly shutting off the flow of vapor through said aperture to the burner, a small flame continuing to burn.
 95 A special feature of our invention is, therefore, a lever having the double function of operating the needle-valve and the cut-off.
 100 The cistern *c* is used with a view of increasing the area of the generating-surfaces and separating the vapors from the supply of gasoline, so as to keep the vapors from interfering with the free delivery of the gasoline into the generating-chamber. The separation of the generating-chamber from the cistern provides 105 practically for the generator a lower part or bottom, which is neither affected by sudden changes of temperature nor the bubbling of the entering fresh and cold gasoline. The box or cistern *c* is made convex on the top, this 110 shape allowing water or other fluids accidentally spilled upon it to run off quickly. The cistern furnishes, in fact, a cushion of air and vapor above the gasoline, upon which elastic cushion the column of gasoline in the pipe *e* 115 rests.
 120 By the construction above described the flame is found to burn steadily under the most difficult conditions—such as the presence of cold-air drafts or the heat of an oven in close proximity to the burner, under which conditions the flames from burners of other descriptions are found to blow and puff and to be generally unsatisfactory.

In Figs. 1 and 2 is shown the application 130

of the invention to a three - burner stove, the construction being such that the vapors are generated by one burner for itself and the other two burners. The stove is shown by 5 A, the lids of which are represented by s, an extension-shelf being shown by t. The gasoline is led from the tank to the burner through the pipe a, as in the construction previously described. In Figs. 1 and 2, however, the end 10 of the pipe is screwed into and closed by a boss, s', formed upon a vertical plate of the stove.

In the application shown in Figs. 1 and 2 the horizontal needle-valve h', with its adjuncts, 15 is called into requisition, the aperture of its tube i" facing the open end of the tube u". The supplemental burners (represented by t' t') are provided with hat-shaped caps, similar to those hereinbefore described. The supplemental burners t' t" are connected by the tube u". The disk i" upon the end of the needle-shaft tube i" keeps the vapor issuing from the aperture of said tube into the pipe u" from 20 igniting by contact with the flame in the rear. It will be understood that the needle-valve tube i" is in communication with the tube h' of the needle-valve h, so that vapor used to supply the first burner is also carried to the second and third burners. A projection, w, 25 on the inner side of the pipe u" is designed to deflect a portion of the vapor to the second burner, a sufficient portion being carried to the third burner; but for the use of the projection w the second burner would receive an 30 insufficient supply of vapor and the third an undue supply.

By the arrangement shown in Figs. 1 and 2 enough vapor is generated by one burner to supply itself and the other two. We do not 35 restrict ourselves to the use together of three burners, as by making the generating-burner large enough it can be made to generate for itself and any other number of smaller ones. Suitable cleaning apertures and plugs with 40 stop-cocks, &c., are used in the various pipes.

Having described our invention, we claim—

1. The combination, with a burner, of a needle-valve in the supply-pipe, a cut-off interposed between the jet-orifice of the supply-pipe and the air-tube of the burner, and a lever connected to said needle-valve and cut-off, and operating both, substantially as set forth.

2. In a vapor-burner, the combination of a cistern, a superimposed generator, a vertical 55 tube extending from the bottom of said cistern and serving as the support of the generator, an apertured tube or thimble extending within the cistern to above the opening of the vertical tube, and a supply-pipe, substantially as set forth.

3. In a vapor-burner, a superimposed generator, a cistern, a vertical tube extending from the bottom of said cistern and serving as the support of the generator, and an apertured tube 60 or thimble extending within the cistern to

above the opening of the vertical tube, combined with a needle-valve and a pipe connecting said valve and generator, substantially as set forth.

4. A generator, a needle-valve in the supply-pipe, a burner, and a cut-off interposed between the jet-orifice of the supply-pipe and the air-tube of the burner, combined with a lever having attachment to said needle-valve and engaging the cut-off, and operating both, substantially as set forth. 70 75

5. In a vapor-burner, a generator, a needle-valve, a tube connecting said generator and needle-valve, a pivoted cut-off interposed between the jet-orifice of the supply-pipe and 80 the air-tube of the burner, and a lever attached to the needle-valve and engaging the cut-off, and operating both, all combined substantially as set forth.

6. In a vapor-burner, a generator, a central 85 air-tube, a needle-valve, a tubular connection between said needle-valve and generator, a pivoted cut-off, and a lever pivoted upon said air-tube, attached to the needle-valve and engaging the cut-off, and serving to operate 90 both, all combined substantially as set forth.

7. In a vapor-burner, the combination of a generator having a tubular center and an annular interior space and gasoline-inlet, an air-tube concentric with and within the said tubular center, leaving a tubular space, q", between the same, a needle-valve below and concentric with the air-tube, and a hat-shaped burner-cap mounted upon the generator and having a space, q', below it in communication with the 95 annular space q", the flange or brim of the cap being slotted and the cylindrical or crown portion perforated, the slots and perforations being radially in line with each other, substantially as set forth. 100 105

8. In a vapor-burner, the combination of the hat-shaped cap having a radially-slotted flange or brim and a perforated crown, the slots and perforations being radially in line with each other, with the generator having a 110 space, q', below the cap in communication with the annular space q", substantially as set forth.

9. The combination, with a vapor-burner, of a generator having a tubular center, an air-tube within and concentric therewith, a needle-valve below and concentric with said tube, and the cup g, substantially as set forth. 115

10. The open supply-tube u", supporting two or more burners and having the projection w, located at the intersection of the burner 120 and supply-tubes, projecting partly across the supply-tube at an angle of about forty-five degrees, combined with a generator and vapor-burner having a jet-orifice coinciding with the open end of the supply-tube, substantially as 125 set forth.

11. The combination, with a burner having an air and vapor induction tube, of a cut-off interposed between the jet-orifice and the induction-tube, a needle-valve closing said jet- 130

orifice, and a lever pivoted upon the induction-tube, attached to the needle-valve and engaging the cut-off, substantially as set forth.

12. The combination, with a vapor-burner, 5 of a cut-off provided with a groove, p' , said cut-off being interposed between the jet-orifice and the induction-tube of the burner, and a lever pivoted upon the induction-tube and having a pin engaging the groove in the cut- 10 off, substantially as set forth.

In testimony whereof we have hereunto set our hands and seals.
